CORE DRILL

Eugene Whinnen, Republic, Mich., assignor to
 Sullivan Machinery Company, a corporation of
 Massachusetts

Application May 23, 1933, Serial No. 672,453

6 Claims. (Cl. 255—72)

This invention relates to core drills, and more particularly to an improved valve mechanism for controlling the flow of circulating fluid in the core barrels of such drills.

5 An object of this invention is to provide an improved core drill. Another object is to provide an improved valve mechanism for the core barrel of a core drill. Still another object is to provide an improved core drill having an improved valve mechanism for controlling the flow of circulating fluid in the core barrel. Yet another object is to provide an improved valve mechanism of the type of the above character wherein the valve thereof is controlled by the 10 pressure of the circulating fluid in the core barrel. A further object is to provide an improved vent valve for the core barrel of a core drill. These and other objects will, however, subsequently more fully appear.

20 In the accompanying drawing there is shown for purposes of illustration one form and two modifications thereof which the invention may assume in practice.

In this drawing,—

25 Fig. 1 is a longitudinal section taken through a swivel type core barrel having embodied therein the illustrative form of the improved valve mechanism.

Fig. 2 is a fragmentary view similar to Fig. 1 showing the valve mechanism in a different position.

Fig. 3 is a cross sectional view taken on line 3—3 of Fig. 1.

Fig. 4 is a fragmentary view of a modified form 35 of valve mechanism.

Fig. 5 is a longitudinal sectional view showing the improved valve mechanism incorporated in a rigid type core barrel.

In this illustrative construction the improved 40 valve mechanism is shown incorporated in a core barrel of the double tube type, and in the preferred form of the invention the valve mechanism is shown embodied in a swivel type core barrel, while in a modified form of construction 45 the improved valve mechanism is shown embodied in a core barrel of the rigid type. It will be evident, however, that the improved valve mechanism may be embodied in core barrels of various other types.

50 In the form of the invention shown in Figs. 1 to 3, inclusive, the improved valve mechanism is shown embodied in a swivel type core barrel and there is shown a hollow drill rod 1 threadedly connected at 2 to a barrel head 3 in turn threadedly connected at 4 to an outer barrel or tube 5.

Threadedly connected to the lower end of the outer tube is an annular core drill bit 6 having usual cutting teeth 7 and a central core passage 8. Rotatably mounted on a ball bearing 9 supported within a chamber 10 formed in the barrel head 3 is an inner plug 11 held in position on the bearing by a hollow holding bolt or pin 12, this pin having a head 13 engaging the upper race of the bearing, while threaded on the lower end of the pin is a nut 14 for holding the plug 11 in position 10 against the lower race of the bearing. This bearing is held in position within the head by a retaining sleeve 15 threaded within the lower end 15 of the head. Threadedly connected at 16 to the inner plug 11 and arranged centrally within and spaced from the outer barrel is an inner core receiving barrel or tube 17 having its lower end guided within a bore 18 formed in the bit. Mounted within the bit between the lower end of the inner tube and a shoulder 19 on the bit is a 20 core retaining ring 20 having resilient core engaging fingers 21 for engaging and locking the core cut by the bit within the inner core receiving tube when the core barrel is raised from the drill hole. Passages 22 connect the upper chamber 23 25 within the head 3 with the space between the inner and outer barrels, as shown in Fig. 1, while passages 24 in the bit conduct the fluid from the space between the barrels through the bit to the bottom of the bit.

30 In the modification shown in Fig. 5, the core barrel is of the rigid type and in this instance the inner core receiving tube 17 is rigidly threadedly connected at its upper end at 25 to a hollow plug 26 in turn threadedly connected at 27 within the lower end of the barrel head 3. In this form of the invention, the ball bearing 9, holding bolt 12 and bearing retaining sleeve 15 are omitted, and the plug 26 engages the threads on the head which are normally engaged by the bearing retaining sleeve. Otherwise this form of the invention is identical to that above described.

35 Now referring to the improved valve mechanism which is shown associated with both types of core barrels, it will be observed that formed centrally within the barrel head 3 is a bore 28 having slidably mounted therein a tubular valve stem or sleeve valve 29. Threadedly secured to the lower end of the valve stem is a retaining nut 30, and the stem is normally held in its raised 40 or closed position with the nut 30 engaging a shoulder 31 on the head by a coil spring 32 encircling the stem and interposed between an enlarged head 33 on the valve stem and the inner end of a reduced bore 34 on the head. ing centrally through the valve stem is a fluid conducting passage 35, while the wall of the stem is traversed by a fluid passage 36. Surrounding the stem and formed in the head 3 is a chamber 5 37 connected to the exterior of the outer barrel through a vent passage 38. Formed at the upper end of the stem and surrounding the upper end of the passage 35 is a tapered valve seat 39 upon which a ball valve 40, shown in Fig. 2, is adapted 10 to seat to close the passage 34.

In the modification shown in Fig. 4, the ball valve 40 is omitted, and the passage 35 in the valve stem is closed by a threaded plug 41.

In the use of the improved core barrel, water 15 under pressure is normally circulated downwardly through the drill rod 1, through the chamber 23 and passages 22, downwardly through the space between the inner and outer barrels and thence downwardly through the bit 20 to wash the cuttings away from the bit, the fluid flowing upwardly exteriorly of the outer barrel from the drill hole. When it is necessary for the circulating drilling fluid to wash downwardly through the inner core receiving barrel when the 25 core drill is lowered into the drill hole, the circulating fluid flows downwardly through the central passage 35 in the valve stem, through the passage in the holding pin 12 into the inner core receiving tube to wash the latter clear of cuttings and debris. After the barrel has been 30 lowered to the bottom of the drill hole, the ball valve 40 is dropped from the ground surface down through the drill rods, and will seat itself on the valve seat 39 on the valve stem to close 35 the passage 35 through the stem. The circulating fluid then flows down through the passages 22, through the space between the tubes and through the passages 24 in the bit to the bottom 40 of the drill hole, thus preventing, during drilling of the core, washing of the drilling fluid over 45 the core, thereby maintaining the latter in its natural state and free from contamination of the drilling fluid. The pressure of the circulating fluid acting on the upper pressure area of the valve stem, when the ball valve 40 is on its seat, causes the valve stem to be forced downwardly against the compression of the coil spring 32 until the passage 36 in the stem is brought 50 into communication with the chamber 37. The inner core receiving barrel is thus vented to the exterior of the outer barrel through the passage in the pin 12, the central passage 35 in the valve stem, chamber 37 and the vent passage 38, leading 55 to the exterior of the barrel, thereby preventing any pressure from building up in the inner tube during drilling of the core and permitting any fluid in the inner barrel to flow therefrom through the vent passage. When the water pressure is reduced, the valve stem is 60 turned to its upper closed position by the coil spring 32, thereby closing the vent. Under certain conditions it is desirable to prevent any flow of the circulating fluid through the valve stem to the inner core receiving tube, and when this 65 is desired, the plug 41 is threaded within the stem to close off the stem passage 35. Other uses and advantages of the invention will be clearly apparent to those skilled in the art.

While there is in this application specifically 70 described one form and two modifications thereof of which the invention may assume in practice, it will be understood that this form and modifications of the same are shown for purposes of illustration and that the invention may be modified and embodied in various other forms without

departing from its spirit or the scope of the appended claims.

What I claim as new and desire to secure by Letters Patent is:

1. In a core drill, a hollow drill rod, a core receiving barrel carried thereby, means providing vent passage means for venting the interior of the core barrel to the exterior of the drill, and valve means for controlling said vent passage means having means for maintaining the same 10 in closed position during lowering of the barrel, and means under the control of the operator for effecting opening of said valve means to effect venting of the interior of the barrel when the drill is in drilling position at the bottom of the 15 drill hole.

2. In a core drill, a hollow drill rod through which a drilling fluid is adapted to flow, a core receiving barrel carried by said drill rod, means associated with said rod and barrel for providing 20 passage means for conducting drilling fluid from said rod through the interior of said barrel to the bottom of the drill during lowering of the barrel into the drill hole, valve means under the control of the operator for cutting off flow of drilling 25 fluid from said rod to the interior of said barrel when the drill is in drilling position at the bottom of the drill hole, and a valve operative when 30 said fluid passage means is closed by said valve means for venting the interior of said barrel to the exterior of the drill, said vent valve being maintained closed while said fluid passage means is open, to prevent flow through the passage to the exterior from affecting the flow from said rod to the interior of said barrel. 35

3. In a core drill, drilling fluid conducting means, an outer barrel, an inner core receiving barrel arranged centrally within and spaced from said outer barrel, means associated with said barrels and fluid conducting means providing passage means for conducting drilling fluid from said conducting means through the inner barrel and through the space between said barrels, valve means under the control of the operator for effecting closure of the passage means for conducting 40 drilling fluid to the interior of the inner barrel so that the drilling fluid at that time flows only through the space between said barrels, and co-operating valve means operative when said passage means for conducting fluid to the inner barrel is closed, for venting the interior of the inner barrel to the exterior of the outer barrel and having means for maintaining the same closed during 50 flow of drilling fluid through said passage means to the interior of the inner barrel. 55

4. In a core drill, drilling fluid conducting means, an outer barrel, an inner core receiving barrel arranged centrally within and spaced from said outer barrel, means associated with said barrels and fluid conducting means providing passage means for conducting drilling fluid from said conducting means through the inner barrel and through the space between said barrels, valve means under the control of the operator for effecting closure of the passage means for conducting 60 drilling fluid to the interior of the inner barrel so that the drilling fluid at that time flows only through the space between said barrels, and co-operating valve means operative when said passage means for conducting fluid to the inner barrel is closed, for venting the interior of the inner barrel to the exterior of the outer barrel and having means for maintaining the same closed during 65 flow of drilling fluid through said passage means to the interior of the inner barrel, said 70 75

latter valve means having means on which the drilling fluid is adapted to act for effecting opening of said vent valve means by the pressure of the drilling fluid.

5. In a core drill, a barrel head, an outer barrel carried by said head, a bit secured to the outer barrel, an inner core receiving barrel arranged centrally within and spaced from the outer barrel, a tubular valve guided in said head, means for supplying circulating fluid through said head and through said tubular valve to the interior of the core receiving barrel during lowering of the drill into the hole, means for interrupting flow of circulating fluid through said tubular valve when the drill is in drilling position at the hole bottom, means for supplying circulating fluid through said head and through the space between the barrels to the drill bit when flow of circulating fluid through said tubular valve is interrupted, said tubular valve being opened by the pressure of the circulating fluid to effect venting of the interior of the core receiving barrel to the exterior of the drill only when flow of circulating fluid through said tubular valve is interrupted.
10. In a core drill, a barrel head, an outer barrel
15. In a core drill, a barrel head, an outer barrel
20. In a core drill, a barrel head, an outer barrel
25. In a core drill, a barrel head, an outer barrel

carried by said head, a bit secured to the outer barrel, an inner core receiving barrel arranged centrally within and spaced from the outer barrel, a tubular valve guided in said head, means for supplying circulating fluid through said head and through said tubular valve to the interior of the core receiving barrel during lowering of the drill into the hole, means for interrupting flow of circulating fluid through said tubular valve when the drill is in drilling position at the hole bottom, said flow interrupting means comprising a valve adapted to be dropped by gravity through the drill head into seated position on the tubular valve to close the passage therethrough, means for supplying circulating fluid through said head and through the space between the barrels to the drill bit only when flow of circulating fluid through said tubular valve is interrupted, said tubular valve being opened when said valve is seated thereon by the pressure of the circulating fluid to effect venting of the interior of the core receiving barrel to the exterior of the drill when flow of circulating fluid through said tubular valve is interrupted.
